[57] CLAIM

The ornamental design for a pet restraining device, as shown and described.

DESCRIPTION

FIG. 1 is a perspective view of a pet restraining device showing my new design, the broken lines being for illustrative purposes only and forming no part of the claimed design;

FIG. 2 is a front elevational view of the pet restraining device.

FIG. 3 is a rear elevational view thereof.

FIG. 4 is a left side elevational view thereof.

FIG. 5 is a right side elevational view thereof.

FIG. 6 is a top plan view of the pet restraining device; and,

FIG. 7 is a bottom plan view thereof.
